ELECTRICAL CAPACITOR OR THE LIKE

James G. Black, Jr., 7517 Inzer St., Springfield, Va.

Filed May 1, 1961, Ser. No. 64,953

Term of patent 14 years

(Cl. D26—1)

FIG. 1 is a front perspective view of an electrical capacitor or the like showing my new design;

FIG. 2 is a rear elevational view;

FIG. 3 is a top plan view;

FIG. 4 is a cross-sectional view taken on line 4—4 in FIG. 2;

FIG. 5 is an end elevational view, the opposite end being substantially a mirror image thereof; and

FIG. 6 is a cross-sectional view taken on line 6—6 in FIG. 2.

Portions of the conductor wires have been broken away in the drawing for convenience in illustration.

I claim:

The ornamental design for an electrical capacitor or the like, as shown and described.
